UNITED STATES PATENT OFFICE.

ERNEST D. WALEN, OF WATERTOWN, AND ARTHUR H. PARSONS, OF GLOUCESTER, MASSACHUSETTS.

MACHINE FOR DETERMINING THE UNIFORMITY OF YARN.

Application filed September 15, 1922. Serial No. 588,509.

To all whom it may concern:

Be it known that we, ERNEST D. WALEN, of Watertown, in the county of Middlesex and State of Massachusetts, and ARTHUR H. PARSONS, of Gloucester, in the county of Essex and said State, both citizens of the United States, have invented a new and useful Improvement in Machines for Determining the Uniformity of Yarn, of which 10 the following is a specification.

The purpose of our invention is to indicate variations in the uniformity of yarn, and it comprises means whereby variations in the yarn will be indicated or recorded in 15 such a manner as to be very much magnified.

Our invention will be understood by reference to the drawings in which it is shown in its preferred form.

Figure 1 is a side elevation of a machine 20 embodying our invention;

Fig. 2 being a plan view thereof.

1 is a table having mounted thereon two uprights 2 between which is carried a bobbin 3 wound with yarn 4. 5 is a guide eye 25 mounted on a bracket on the table 1. 6 is a stationary foot mounted on a micrometer 61 supported from an upright by means of a strap 8. By means of the micrometer the height of the foot can be adjusted positively 30 and the adjustment measured. The top of this foot is a flat surface or table 10. Its support carries two eyes 9 which are in line with the guide eye 5, one on each side of the table 10 over which the yarn is drawn, so 35 that the yarn passing from the bobbin to the guide eye 5 will thence proceed in a straight line through one of the eyes 9 across the table 10, thence through the other eye 9 to a second guide eye 11 supported on the table 40 1. From the guide eye 11 the yarn passes between a pair of feed rollers 12 and 13. By means of these rollers the yarn is drawn by the path above described from the bobbin 3. Power is applied to the roller 12 by 45 means of a shaft 14 on which the roller 12 is mounted, the shaft 14 being connected with a suitable source of power.

On top of the stationary foot or support 6 rests a movable foot 15 which is hung 50 from a roller 16 on the upright 7 and carrying a weighted arm 17, the sliding weight on which is usually adjusted to counter-balance the weight of the movable foot 15, or it may be adjusted to vary the pressure 55 of the foot on the yarn as desired. This

construction is such that any variation in the yarn which passes between the stationary foot 6 and the movable foot 15 will lift the movable foot and this movement will allow the weighted arm to turn the roller 16. 151 60 are straps attached to the upright 7 in which straps the foot 15 moves.

The roller 16 carries a vertical mirror 18, and it will be seen that any movement given to the roller 16 will cause a movement of 65 the mirror 18 about a horizontal axis.

Opposite the mirror 18 is a drum 19 which is closed light-tight except for a small opening 20. Within the drum is located a light, preferably an electric bulb 21. On a stand 70 22 on the table 1 is adjustably mounted a lens 23.

It will be noted from Fig. 2 that these parts are so adjusted that a beam of light from the bulb 21 will pass through the lens 75 23 and strike the mirror 18. From the mirror 18 it will be reflected as a point of light to a strip of paper 24 which is caused to pass around two spools 25 and 26 to present a flat surface. This paper is a sensitized paper such that the beam of light reflected upon it by the mirror will act photographically thereon, and the result will be such an indication as is shown in Fig. 1 80 at 27, this wavy line indicating variations in 85 the thickness of the yarn.

To cause the feeding of the photographic strip I continue the shaft 14 along the table 1 providing it with bearings as at 28 and 29. At its end is a bevel gear 30 which is in mesh 90 with a bevel gear 31 mounted on a vertical shaft 32 which carries a spool 26. By this means the shaft 32 and spool 26 are turned. 34 is a presser roll which engages and directs the passage of the photographic strip 95 24. The spool 25 is mounted on a similar shaft 35 which encloses the gears 30 and 31. A crossbar 37 connects the upper ends of the shafts 32 and 35. Arms 38 mounted on the shaft 32, one of these arms being located 100 under the spool 26 and the other just above it, have pivoted thereto by rod 391 levers 39 one end of each of which serves as a bearing for the presser roll 34, the other end being attached by a spring 40 to the top of 105 the casing 36. A similar construction provides a presser roll 341 for the spool 25. The spool 26 is thus a feed or draft roll for the photographic strip which is thus caused to travel from a magazine roll (not shown) 110

in front of the mirror 18 and at a proper speed with relation to the speed of the yarn, it being held under tension by the presser rolls 34, 341. Any irregularities causing the 5 rising and falling of the movable foot will be magnified very much and properly recorded on the photographic strip.

We prefer to mount the table on the stationary foot on a micrometer secured so that 10 the level of the table may be adjusted according to the diameter of the yarns.

Our invention may be otherwise embodied, but the above is a simple and, as it has been proved, an efficient and accurate way of 15 determining the irregularities in a yarn,—irregularities which because they are minute cannot be determined except by enlargement.

What we claim as our invention is:—

- 20 1. In a machine of the kind described, a fixed member to support the moving yarn, a movable member, means for supporting said movable member above said fixed member for movement perpendicularly to the yarn supported by the fixed member, means for drawing the yarn between said members, and means operable by said movable member whereby the movements of said movable member may be indicated.
- 25 2. In a machine of the kind described, a fixed member to support the moving yarn, a movable member, means for supporting said movable member above said fixed member for movement perpendicularly to the yarn supported by the fixed member, means for drawing the yarn between said members,
- 30 3. In a machine of the kind described, a fixed member to support the yarn, a movable member mounted to move with each variation in the thickness of said yarn, means for supporting said movable member above said fixed member for movement perpendicularly to the yarn supported by the fixed member, means for drawing the yarn between said members, and means operable by said movable member whereby the movement of said movable member may be indicated, said means comprising a mirror to be moved by said movable member to make an indication by reflection.
- 35 4. In a machine of the kind described, an adjustable fixed member to support the yarn, a movable member, means for supporting said movable member above said fixed member for movement perpendicularly to the yarn supported by the fixed member, a rotatable support for said movable member, a connection between said movable member and said support, means connected to said support to counterbalance said movable member, a mirror mounted on said rotatable member to be moved therewith, means for throwing a beam of light thereon to be reflected therefrom, and means for receiving said reflected beam of light whereby movements of said movable member will be indicated.

ERNEST D. WALLEN.
ARTHUR H. PARSONS.
